Res. 573

Jam'l. D. Vose, of Albany, N.Y.

Letters Patent No. 573. Dated June 28th 1853.

Ante-dated May 2, 1853.

The schedule referred to in these Letters Patent and making part of the same

To all whom it may concern:

Be it known that I, Jam'l. D. Vose, of Albany, county of Albany
State of New York, have invented or produced a new design for a cooking stove (A) and I do hereby declare that the following is a full & exact description of the same, reference being had to the annexed drawings making part of this specification.

My invention not being easily described in words, reference to the drawings is made.

In the drawings the letter S, refers to the top plate of the stove

"	S.	"	"	"	side	"	"	"	"
"	F.	"	"	"	front	"	"	"	"
"	H.	"	"	"	hearth	"	"	"	"
"	B.	"	"	"	Back	"	"	"	"
"	D.	"	"	"	Doors	"	"	"	"
"	I.	"	"	"	legs	"	"	"	"

My invention has no reference to any single moulding or ornament on said plates, but consists in the configuration & disposition of the ornaments in combination with the mouldings.

I claim no separate configuration or part.

Des. 573

What I claim as my invention & desire to secure by letters patent of the United States, is the combination of mouldings & ornaments as arranged with cooking stove (A.), the whole forming an ornamental design.
